US00D943739S

(12) **United States Design Patent** (10) **Patent No.:** **US D943,739 S**
Alkmin et al. (45) **Date of Patent:** **** Feb. 15, 2022**

(54) **ABSORBENT ARTICLE**

(71) Applicant: **Johnson & Johnson Consumer Inc.**, Skillman, NJ (US)
(72) Inventors: **Marco Antonio Alkmin**, Sao Paulo (BR); **Marcelo N. Pitta**, Sao Paulo (BR)
(73) Assignee: **Johnson & Johnson Consumer Inc.**, Skillman, NJ (US)

(**) Term: **15 Years**(21) Appl. No.: **29/775,556**(22) Filed: **Mar. 24, 2021****Related U.S. Application Data**

(62) Division of application No. 29/684,233, filed on Mar. 19, 2019, now Pat. No. Des. 917,692.
(51) **LOC (13) Cl.** **24-04**
(52) **U.S. Cl.** USPC **D24/125; D24/124**

CLAIM

We claim the ornamental design for an absorbent article, as shown and described.

DESCRIPTION

FIG. 1 is a perspective view of an absorbent article according to an embodiment of the present invention; FIG. 2 is a top plan view of the absorbent article of FIG. 1; FIG. 3 is a side view of the absorbent article of FIG. 1; FIG. 4 is a bottom plan view of the absorbent article of FIG. 1; FIG. 5 is a first end view of the absorbent article of FIG. 1; and, FIG. 6 is a second end view of the absorbent article of FIG. 1.
